HANDWHEEL FOR A VALVE

Paul J. Natho, 3742 Turnberry, Houston, Tex.

Filed June 1, 1962, Ser. No. 70,378

Term of patent 14 years

(Cl. D78—1)

FIG. 1 is a top plan view of a handwheel for a valve showing the new design.

FIG. 2 is a bottom plan view of the handwheel.

FIG. 3 is an elevational view of the handwheel.

I claim:

The ornamental design for a handwheel for a valve, substantially as shown.
